UNITED STATES PATENT OFFICE.

LUCA PATERNOSTRO, OF DALLAS, TEXAS.

DESIGN FOR A HEEL-BRACE FOR SHOES.

59,866.

Specification for Design.

Patented Nov. 29, 1921.

Application filed August 25, 1920. Serial No. 406,024. Term of patent 14 years.

To all whom it may concern:

Be it known that I, LUCA PATERNOSTRO, a subject of the King of Italy, residing at Dallas, in the county of Dallas and State of Texas, have invented a new, original, and ornamental Design for a Heel-Brace for Shoes, of which the following is a specification, reference being had to the accompanying drawing, forming part thereof.

Figure 1 is a side elevation of a heel brace showing my design.

Fig. 2 is a transverse sectional view of the same, and

Fig. 3 is an underside view of the same.

I claim—

The ornamental design for a heel brace for shoes as shown.

LUCA PATERNOSTRO.
